UNITED STATES PATENT OFFICE.

WINFIELD HANCOCK YOST, OF MONTREAL, QUEBEC, CANADA, ASSIGNOR TO RODGER
BALLAST CAR COMPANY, OF CHICAGO, ILLINOIS, A CORPORATION OF MAINE.

BALLAST-CAR.

1,116,863.

Specification of Letters Patent. Patented Nov. 10, 1914.

Application filed September 14, 1912. Serial No. 720,367.

To all whom it may concern:

Be it known that I, WINFIELD HANCOCK YOST, a citizen of the United States of America, residing at Montreal, in the Province of Quebec, Canada, have invented certain new and useful Improvements in Ballast-Cars; and I do hereby declare that the following is a full, clear, and exact description of the same.

10 This invention relates more particularly to ballast cars of the type adapted to have their loads discharged by the passing of a plow therethrough and it has for an object to provide the car ends with improved 15 means for guiding the plow unto the car.

A further object is to provide an improved locking device for the side doors which will be less liable to injury by the material as it is discharged from the car.

20 For further comprehension however of my invention and of the objects and advantages thereof reference will be had to the following description and the appended claims, and to the accompanying drawings 25 forming part of this specification in which similar reference characters indicate the same parts and wherein;

Figure 1 is a side elevation of the end portion of a ballast car having the invention embodied therein, Fig. 2 is a plan view thereof partly broken away, Fig. 3 is an enlarged detail horizontal section on the line 3—3 Fig. 1, Fig. 4 is a transverse view of the car, being partly in end elevation 35 and partly in section on the line 4—4 Fig. 2, Fig. 5 is a detail vertical section on the line 5—5 Fig. 3, and Fig. 6 is a side elevation of the portion of the car shown in Fig. 5. Fig. 7 is a detail sectional elevation illustrating particularly the pawl for locking the movable shaft in raised position.

The flooring of the car is shown at 1, being supported on the usual understructure comprising a center sill 2, side sills 3 and cross bearers 4. The movable side wall sections or doors, are shown at 5 and are hinged at 6 to the top rails 7, these parts being all of any ordinary or approved construction.

The side stakes 8 supporting the top rails 7 and which form the supporting members of the side walls are preferably made, as shown most clearly in Fig. 4, of fish-belly for-

mation with their inner sides straight and 55 their outer faces swelling out from top and bottom to a point adjacent the flooring 1, this construction providing a stake with increased strength to resist outward bending strains at the point where strains from 60 the plow will be transmitted thereto. As shown most clearly in Fig. 3 these stakes may be made of pressed or cast metal presenting on their inner sides right angle flanges 10 by means of which they are secured in the usual manner to the side sills 3, the main stake members being braced by the angle irons 11 secured by one flange to the side sills and by the other to the web of the said main side stake member. 70 As shown clearly at α in Fig. 3 the side edges of the door are checked out to fit over the edges of the side stake and insure a tight joint between the doors and stakes. In order to provide means for properly 75 guiding the plow onto the car the angle irons 11 which brace the stakes at the car corners have their longitudinally disposed flanges turned toward the ends of the car and widened and bent or flared outwardly 80 approximately midway of their width the bent out portions forming an obtuse angle with the portions parallel to the car sides.

My improved means for locking the doors 5 in closed position comprises a pair of 85 shafts 15, one at each side of the car, these shafts extending through slots 16 in the side stakes 8 and being bodily movable therein, the slots extending a short distance above and below the flooring 1 and being 90 substantially vertical throughout the major portion of their length but curving inwardly at their lower ends under the edge of the flooring as shown at 16'. Secured upon each of these shafts are a series of 95 sleeves 17, the shafts being here shown as hexagonal and the sleeves having correspondingly formed interiors. These sleeves are located at the points where the shafts pass through the stakes that is to say between the adjacent doors. Each of these sleeves carries substantially midway of its own length a fixed pinion 18 adapted to engage with a rack formed by a series of longitudinally projecting pins 19 secured to 100 the side stake, so that upon rotation of the shaft it will be caused to move bodily upward or downward in the slots. Secured

- upon each of these sleeves, one between the pinion and each end of the sleeve and in position to engage the doors, are a pair of hooked fingers 20 which are adapted to
- 5 engage the door as it hangs normally in a slightly open position as shown at the right of Fig. 4 and move it inwardly to allow the shaft to move upwardly outside the doors, the sleeves when in the upper ends
- 10 of the slots bearing against the door battens 5' and locking the doors against outward movement, the lower edges of the battens 5' being beveled as shown to prevent any chance of the sleeves catching thereon.
- 15 Secured to the door battens 5' and projecting outwardly are small vertical plates 25 having their under side notched as at 26 to form hooks fitting over the sleeves 17 and serving to positively hold the doors 20 against inward movement.

As will be readily seen, when the shafts are in a position to have the doors hang free they will be underneath the edges of the car flooring and covered thereby, because of the inward curving of the lower ends of the slots, the shafts thus being protected from the load being discharged from the car. The shaft is retained in position in the upper ends of the slots and in locking engagement with the doors by means of pawls 28 pivoted at 29 to the corner stakes and recessed to present shoulders adapted to engage under the shafts and prevent downward movement thereof, the shafts being released by knocking the ends of the pawls to swing the shoulders from underneath the shafts.

What I claim is as follows:

1. In a car adapted to discharge material 40 through the side, a side door and side door locking means including a rolling shaft adapted to lock the door in closed position and be moved to release the door, such shaft being, when the door is released, out of the 45 path of the material discharging through the car side.

2. In a ballast car, side door locking means including a rolling shaft adapted to travel from a position in contact with the 50 door to a position underneath the car flooring.

3. In a ballast car having a fixed floor and side door, locking means for such door comprising a rolling shaft adapted to move 55 from a position below the surface level of the fixed floor to a position to lock the side door.

4. In a ballast car, a side door, a member upon the door and a bodily movable shaft 60 adapted to assume a position between the door and said member to hold such door against both outward and inward movement.

5. In a ballast car, side dump door locking means comprising a bodily movable

shaft adapted to move from a position under the flooring across the edge of the latter into locking engagement with the door.

6. In a ballast car, side dump door locking means comprising a shaft adapted to be moved bodily up and down adjacent the lower edge of the door, means for operating such shaft, and means for guiding such shaft under the edge of the car flooring 75 when moved downwardly.

7. In a ballast car, side dump door locking means comprising a shaft having fingers adapted to engage the door in advance of the shaft, the said shaft being adapted to 80 hold the door in closed position independently of the said finger.

8. In a ballast car, side dump door locking means comprising a bodily movable shaft having fingers adapted to engage the 85 door in advance of the shaft.

9. In a ballast car, side dump door locking means, comprising, side stakes having slots extending longitudinally thereof adjacent the lower edges of the doors, a shaft 90 extending lengthwise of the car through the said slots, and a rack and pinion engagement between the said shaft and the car whereby the said shaft may be caused to move bodily into and out of position to 95 lock the said doors against outward movement.

10. In a ballast car, side dump door locking means comprising, side stakes having slots extending longitudinally thereof, adjacent the lower edges of the doors and curved inwardly at their lower ends, a shaft 100 extending lengthwise of the car through the said slots, and a rack and pinion engagement between the said shaft and the car 105 whereby the said shaft may be caused to move bodily into and out of position to lock the said doors against outward movement.

11. In a ballast car, side dump door locking means, comprising, side stakes having slots extending longitudinally thereof adjacent the lower edges of the doors, and curved inwardly at their lower ends under the side edges of the car flooring, a shaft 115 extending lengthwise of the car through the said slots, and a rack and pinion engagement between the said shaft and the car whereby the said shaft may be caused to move bodily into and out of position to lock 120 the said doors against outward movement.

12. In a ballast car, side dump door locking means comprising, side stakes having slots extending longitudinally thereof adjacent the lower edges of the doors, a shaft 125 extending lengthwise of the car through the said slots, means for moving the said shaft bodily in the said slots whereby it may be moved into position to lock the said doors against outward movement, and a 130

plurality of fingers carried by the shaft and adapted to engage the door in advance of the shaft and move it to closed position.

13. In a ballast car, side dump door locking means comprising, side stakes having slots extending longitudinally thereof adjacent the lower edge of the doors, a shaft extending lengthwise of the car through the said slots, means for moving the said shaft bodily in the said slots whereby it may be moved into position to lock the said doors against outward movement, and a member upon the door having a hook adapted to take over the shaft to hold the door against inward movement.
14. In a ballast car, side dump door locking means comprising, side stakes having slots extending longitudinally thereof adjacent the lower edges of the doors, a shaft extending lengthwise of the car through the said slots, means for moving the said shaft

bodily in the said slots whereby it may be moved into position to lock the said doors against outward movement, a plurality of fingers carried by the shaft and adapted to engage the door in advance of the shaft and move it to closed position, and a member upon the door having a hook adapted to take over the shaft to hold the door against inward movement.

25

15. In a ballast car side stakes of fish belly form having their greatest width adjacent the car flooring the said stakes being longitudinally slotted at such points to receive a bodily movable door locking shaft.
